UNITED STATES PATENT OFFICE.

HENRY SCHILD, OF BALTIMORE, MARYLAND.

DESIGN FOR A NECK-RUCHING.

SPECIFICATION forming part of Design No. 11,567, dated January 6, 1880.

Application filed October 14, 1879. Term of patent 3½ years.

To all whom it may concern:

Be it known that I, HENRY SCHILD, of Baltimore city, State of Maryland, have originated and designed a Pattern for Neck-Ruching, of which the following specification is a full, clear, and exact description, reference being had to the accompanying drawing.

A represents the neck-band of the ruching, to which is stitched at *a* the plaiting or fluting 10 B, which tapers away, as shown at *b b*, in front. This plaiting or fluting consists of a series of folds practically vertical at the outer edge, as illustrated, but horizontal and flat at the line of attachment to the neck-band.

15 The part B is turned over so as to be about at right angles to the band, or at a greater angle than ninety degrees.

What I claim as my invention is—

1. The design for a neck-ruching, consisting of a plain neck-band, A, and plaited or fluted portion B, the latter being attached directly to the band and wholly at or about at right angles to the same, substantially as described, and shown in the accompanying illustration.

2. The design for neck-ruching, consisting of the plain neck-band A and plaited or fluted portion B, attached directly to the band and at about right angles thereto, and tapering away in front, as described, and shown in the accompanying drawing.

HENRY SCHILD.
